GAME BOARD

Gordon A. Barlow, Evanston, Ill., assignor to Marvin
Glass & Associates, Chicago, Ill.

Filed June 11, 1970, Ser. No. 23,436

Term of patent 14 years

Int. Cl. D21—01

U.S. Cl. D34—5

FIG. 1 is a perspective view of the game board showing my new design;

FIG. 2 is a rear elevational view of the game board;

FIG. 3 is an end view of the game board, both ends being identical in appearance;

FIG. 4 is a top plan view of the game board; and

FIG. 5 is a bottom plan view of the game board.

I claim:

The ornamental design for a game board, substantially as shown and described.
